(57) **CLAIM**

The ornamental design for a body for a portable home comfort appliance, as shown and described.

DESCRIPTION

FIG. 1 is a right side front perspective view of a body for a portable home comfort appliance showing my new design; FIG. 2 is a rear perspective view thereof; FIG. 3 is a front elevation view thereof; FIG. 4 is a side elevation view thereof, the opposite side being a mirror image of that shown; FIG. 5 is a rear elevation view thereof; and, FIG. 6 is a top plan view thereof.

The broken line showing of environmental structure in FIGS. 1-6 is for illustrative purposes only and forms no part of the claimed design.
